UNITED STATES PATENT OFFICE.

MATHEW SPINELLO, OF KANSAS CITY, MISSOURI.

ELEVATOR-HATCHWAY-DOOR-OPERATING DEVICE.

1,393,918.

Specification of Letters Patent.

Patented Oct. 18, 1921.

Application filed March 2, 1920. Serial No. 362,731.

To all whom it may concern:

Be it known that I, MATHEW SPINELLO, a citizen of the United States, residing at Kansas City, in the county of Jackson and State of Missouri, have invented certain new and useful Improvements in Elevator-Hatchway-Door-Operating Devices; and I do declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to an elevator hatchway door operating device and particularly to means for operating the door to an open position only after the elevator cage has reached a landing stage. It is also provided with means whereby the door will be automatically shifted to a closed position when the elevator has begun to move away from the landing, thereby insuring that the door will be closed unless the elevator is in close proximity thereto.

In the illustrated embodiment of the invention, means is shown for controlling a pneumatic operated mechanism on the wall of the elevator shaft in response to a pedal actuated device on the elevator cage so that the door may be shifted to an open position, the pedal actuating device being effective to accomplish the desired result only when the floor of the elevator is in alignment with the actuating mechanism of the air control.

In the drawings,

Figure 1 is a diagrammatic view of the operating mechanism for the door of the pedal actuating device in position to open the pneumatic control.

Fig. 2 is an end view of the same.

Fig. 3 is a diagrammatic view of the pneumatic control valve or gage and Fig. 4 is a side elevated view of the pneumatic control or valve.

Referring now to the drawings by numerals, 1 designates the elevator cage arranged to move vertically in a conventional elevator shaft, and 2 denotes the floor of the cage. Projecting through the floor 2 is a pedal-rack 3, having at its upper end a pedal 4, between which and the floor is a spring 5, normally holding the pedal 4 in a position above the floor.

The rack portion of the member 3 meshes with a gear or pinion 6, mounted in a bracket 7 carried by the floor 2, the gear or pinion being relatively long so that its teeth may also engage a horizontal rack bolt 8 supported at 9 and 10 beneath the floor 2.

The rack bolt 8 is provided with a wedge shaped end 11, for the purpose of riding the cams 12 and 13 on a suitable frame or plate 14, mounted in a convenient manner, but effective to operate certain mechanism to shift the door 15 to an open or closed position dependent upon the position of the cage, on the wall of the elevator shaft. Between the cams 12 and 13 is a horizontal, shiftable, pneumatic valve control 16 which is supported by the bearings 17 and 18 on the plate 14; the rack 16 being provided with teeth 19 constituting a control for the valve 21 and by referring to Figs. 3 and 4 it will be observed that the valve 21 is provided with a stub shaft 22 mounted in the bearing 23 of the bracket 24 carried by the plate 14. It will also be observed that the valve 21 is in axial alignment with the valve 25 in which it is received, the valve 25 being mounted on the plate 14. Provided at one end of the segmental rack 23 is an upstanding lever 26 to which is connected a tension spring 27, anchored at 28 to the wall of the elevator shaft. Therefore as the member 16 is moved in one direction the segmental rack 20 is moved in a clock-wise direction against the tension of spring 27, but as soon as the pressure against the member 16 is relieved, the spring will rotate the valve 21 in contra-clockwise direction, the movement of the valve 21 being effective in admitting air to the motor of the door operating mechanism.

The motor is best shown in Fig. 1, as consisting of a cylinder 29, having a piston 30 to which is connected a piston rod 31 passing through a gland or packing box 32 through one end of cylinder 29. The piston rod 31 is provided with a bifurcated end 33 through which projects a bolt 34 in the slot 35 of the link 36 and the lower end of the crank is pivoted at 39 to a bell-crank lever 40, which is pivoted to the door at 41 and it is provided with a notched head 42 to engage the keeper 43 on the hatch-way wall.

The cylinder is supplied with fluid for projecting the piston 30 from the right to left through the medium of pipe 44 supplied

through the valve or control mechanism consisting of the valve 21 and cylinder 25 and the pipe 44 is shown as connected to the valve casing 25, in Fig. 3, so it may be supplied with fluid through a Y-shaped port 45 in the valve member 21 when the branch 46 registers with the supply pipe 47 connected with the underside of the casing 25 and in communication with the cylinder 29. 5
10 On the end opposite to the end which is connected with the pipe 44 is a pipe 49, and said pipe is attached to the supply pipe 47 through the casing 25 when the part 50 of the port 45 registers with the pipe 47 and the 15 upper part registers with the port 49. When the pipe 49 is being supplied the branch 46 of the port 45 will not be in registration with the port 47 nor will the upper end be in registration with the port 44, pipe 44 will, 20 however, have registration with port 51 when pipe 49 is being supplied with air and as soon as groove 51 communicates with a through-port 52 adapted to communicate with pipe 53 the air on the right side of piston 30 in cylinder 29 will be supplied while the air on the left side of piston 30 is exhausted. 25

As the valve 21 is drawn so that the branch 36 communicates with 47 the pipe 49 will 30 communicate with groove 54 which communicates with through port 44 similar to port 52 and while ports 44 and 55 will be communicating with pipe 53 so that the cylinder of the left end of piston 30 will be in 35 communication with the exhaust.

From the foregoing it will be apparent that I have provided a simple, durable and efficient elevator hatchway door operating device which may be applied to any type of 40 elevators without change of construction thereof.

What I claim and desire to secure by Letters-Patent is:

1. In a hatchway door operating mechanism, a door operating member, a motor connected to said door operating member comprising a cylinder and a reciprocatory member in the cylinder, pipes connected to opposite ends of said cylinder, a fluid pressure supply means for alternately connecting the 50 pipes to the supply and to atmosphere, a movable member, a pedal rack carried thereby, a pinion operated by the pedal rack, a rack bolt meshing with the pinion and engageable with the valve operating mechanism, and means for retracting the rack bolt. 55

2. In a hatchway door operating mechanism, an air operated motor for opening and closing a door, a valve mechanism for effecting reversal of the motor, said mechanism including a valve, a spring-actuated lever connected to the valve, a segmental rack on said valve, a sliding rack member engaging the segmental rack, a movable elevator cage, and a foot pedal actuated bolt for moving 60 the sliding rack in one direction to oppose the spring and thereby reverse the valve. 65

3. In a hatchway door operating mechanism, a door operating member, a latch connected thereto and movable into and out of 70 latching position in response to movement of the door operating member, a motor connected to said door operating member, fluid pressure means for operating the motor, an elevator cage, a pedal rack carried thereby, a 75 pinion operated by the pedal rack, a rack bolt meshing with the pinion and movable into and out of fluid-pressure-supply-means operating position, and means for retracting the rack bolt. 80

In testimony whereof I affix my signature.
MATHEW SPINELLO.
